UNITED STATES PATENT OFFICE.

DAVID McCURDY, OF OTTAWA, OHIO, ASSIGNOR TO THE OTTAWA GATE MANUFACTURING COMPANY, OF SAME PLACE.

HINGE.

SPECIFICATION forming part of Letters Patent No. 282,004, dated July 24, 1883.

Application filed May 19, 1883. (Model.)

To all whom it may concern:

Be it known that I, DAVID McCURDY, a citizen of the United States, residing at Ottawa, in the county of Putnam and State of Ohio, 5 have invented certain new and useful Improvements in Hinges; and I do declare the following to be a full, clear, and exact description of the invention, such as will enable others skilled in the art to which it appertains to 10 make and use the same, reference being had to the accompanying drawings, and to letters or figures of reference marked thereon, which form a part of this specification.

Figure 1 of the drawings is a front view. 15 Figs. 2 and 3 are detail views of the hinge.

This invention has relation to devices for connecting a gate to the gate-posts; and it consists in the construction and novel arrangement of the hinges, as hereinafter set forth, 20 and particularly pointed out in the appended claims.

In the accompanying drawings, the letter A designates a gate of any ordinary construction, having the rear stile, B, and the front 25 stile, C. In a mortise of the front stile is pivoted the latch D, which is of angular form, having an upwardly-extending middle portion, e, from the upper end of which extends inward the handle g, and from the lower portion 30 of which extends outward the latch-projection h, which terminates in a beveled end, k. This latch is pivoted at its upper angle, as indicated at l, so that it hangs pendent, its center of gravity being so arranged with reference to the pivot that the latch-projection 35 hangs in horizontal position. Therefore no guard is needed, as it will engage the strike properly as the gate swings to. It is not intended that this latch should be claimed in 40 the present application; but the right is herein reserved to make a future separate application therefor.

E represents the upper hinge, which consists of the eye-section a and the pintle-section b. The latter section, which is usually attached to the gate-post, consists of the back plate, c, and the lug m, from which the pintle n rises. From the back of the plate c projects a stud, p, which is designed to enter a recess in

the post, and open end slots, s, are made in the 50 ends of the plate to receive the fastening screws or bolts. In this manner the hinge-section is formed so that it can be readily cast, no drilling being afterward required. The screws or bolts hold it firmly to the post, and the stud 55 p prevents it from moving vertically out of position.

a represents the eye-section of the upper hinge, also consisting of a back piece, v, and a lug, r, in which is formed the eye-bearing w. 60 In the lower part of the back flange, v, is made an open-end slot, s, and the back flange is also provided with a rearwardly-projecting stud, p, and by means of said stud and a bolt or screw passing through the slot the eye-section 65 is firmly attached to the stile of the gate.

F designates the lower hinge, which consists of the pintle-section G and the eye-section H. The former consists of the back plate or flange, K, and the horizontal lug L, from which rise 70 two laterally-arranged pintles, P P. The upper portion of the flange K is formed with the open-end slots s s, and from the rear of said flange projects a strong stud, p'. This section of the hinge is secured to the lower portion of 75 the gate-post, its stud entering a recess therein, and screws or bolts passing through the slots.

The eye-section H consists of a back flange, N, and a horizontal lug portion, T, having a 80 deep central rib, R, extending downward from its under side, and formed with projection from its lower portion to serve as a stop-lug, as indicated at z. The horizontal portion T is formed with open eye-bearings V V, the 85 walls of which are only partial, being open in rear, as indicated at a'. These bearings V V, respectively, engage the pintles P P of the other section of this hinge. The flange N of the section H is formed with a rear stud, p'', 90 and with an open-end slot, s, so that it can be firmly fastened to the stile of the gate. When it engages the pintle-section G fully, both bearings V V being on the pintles, the stop-lug z projects under the horizontal portion L of the 95 pintle-section and prevents the gate from being lifted and thrown off its bearings by the efforts of pigs or other small animals. All of

these hinge-sections are readily and cheaply cast, and require no after-drilling to render them serviceable.

The lateral arrangement of the pintles P 5 and the bearings V is designed to provide means to render the gate automatic or self-closing from either side. When the gate is opened at a right angle, or more, it will be held open by its own weight, the vertical plane of 10 its center of gravity extending back of the pintle of the lower hinge, against which it rests. When, however, the gate is opened at a less angle, it will be automatically closed.

Having described this invention, what I 15 claim, and desire to secure by Letters Patent, is—

1. Sectional hinge-castings having back flanges formed with open-end slots *s* and rear studs, *p*, substantially as specified.

2. The combination, with the double lateral 20 pintle-section G, of the section H, having the lateral partial eye-bearings V V and the central rib extended to form the stop-lug *z*, substantially as specified.

In testimony whereof I affix my signature in 25 presence of two witnesses.

DAVID McCURDY.
